UNITED STATES PATENT OFFICE.

ASA L. PARRISH, OF ELKHART, INDIANA.

METHOD OF MAKING PAPER BAGS.

971,780.

Specification of Letters Patent.

Patented Oct. 4, 1910.

Application filed May 24, 1909. Serial No. 497,999.

To all whom it may concern:

Be it known that I, ASA L. PARRISH, of Elkhart, in the county of Elkhart and State of Indiana, have invented an Improved 5 Method of Making Paper Bags, of which the following is a specification.

My invention relates to the manufacture of what are known as square bottom paper bags from tucked tubing, and the objects 10 of my improvements are to perform operations upon the tubing from which the bags are made, that will assist in opening out the end of a bellows tucked tube into the well known diamond form, thereby enabling me 15 to make bags with a machine which requires less mechanism in its diamond forming section than other machines of this class.

In the accompanying drawings, Figure 1 is a length of bellows tucked tubing showing 20 some of the operations which are performed upon it. Fig. 2 is a continuation of Fig. 1, showing further operations. Fig. 3 is a bag section with the bottom spread into the diamond form. Figs. 4, 5, and 6, show further 25 operations toward completing the bag. Fig. 7, shows the bag bottom being spread into the diamond form.

Similar figures refer to similar parts throughout the several views.

Referring to Fig. 1, 2 is the well known thumbhole tip which may be formed in the paper by any well known cutting means, and at distances apart corresponding to the length required for bag tubes, and the tip 35 2 is compelled to stand at an angle with the tubing for reasons later explained.

3, 3, 3, 3, are creases made in the tucked tubing, and extend from the outer edges of the tubing toward the center a distance 40 which is substantially the depth of the side tucks. It will be seen that these creases 3, 3, 3, 3, are all made toward the inside of the tube which shows the creases in opposition to each other. As shown in Fig. 1, the under side of the tube and the bottom half of the bellows tuck are creased upward, and the upper side of the tube and the upper half of the bellows tuck are creased downward. The creases 3, 3, 3, 3, are made in 45 the tubing at the proper position for the corners 4, 4, 4, 4, of the bag bottom to be formed, and also the side folds of the bottom 5, 5.

In the operation of opening out a tucked 55 tube and spreading a diamond form on the end of it, it is well known how difficult it

is to fold the sides 6, 6, of the diamond in an inward direction, and complicated and expensive operative mechanism is necessary in most bag machines to overcome the difficulty. It will be seen (Fig. 7.) that when the side tucks of the tubing are spread apart in the operation of forming the diamond, the creases 3, 3, 3, 3, will become straight creases on lines 5, 5, and when the side tucks are spread apart on lines 5, 5, the creases 3, 3, 3, 3, assume the position of having been creased from the inside of the tube, and consequently the sides 6, 6, of the diamond are inclined inwardly and will fold 60 into the desired diamond form very readily, and without the use of much mechanism. 65

The tube lengths are cut as shown at 7, 7, (either rough or smooth edged) on a line back of the forward line of the thumbhole tip thereby leaving a thumb hole 8, at the open end of the bag. The tip 2, extending across the cutting line is creased or bent in any convenient manner, substantially on line 9, 9, compelling it to stand at an angle 70 with the tube, and placing it in a position 75 back and clear of the cutting blade. The tube is cut through all of the plies leaving in the center of the under sheet a narrow uncut connection 10, between the tube 80 lengths. After the cutting has been done the end of the tube is opened out into the diamond form, the uncut connection 10 with the preceding bag tube drawing on the front 85 end of the oncoming blank, and assisting in 90 making the diamond form of the bag bottom. During the time that the diamond fold is being formed the upper side of the tube is bent over the edge of a blade on line 12, 12. The diamond form is then pressed 95 and paste 13, is applied in any well known manner. The uncut connection 10, is then severed, and the well known final folds 14 and 15 are made, by which the bag bottom is 100 closed.

Having described my invention, what I claim and desire to secure by Letters Patent is—

1. The herein described improvement in the method of making paper bags, comprising forming bellows tucked tubing from a sheet of paper, forming the creases 3, 3, 3, 3, in the opposite faces of the tubing and its tucks in opposite directions toward each other, cutting the tubing and forming the 105 diamond fold and final folds of the bag bottom and completing the bag.

2. The herein described method of making paper bags, consisting of forming a sheet of paper into bellows tucked tubing, cutting a thumbhole tip in the paper either before or after it is formed into tubing, compelling the tip 2, to stand at an angle with the tubing, creasing the tucked tubing at positions where the corners of the bag bottom are to be formed from both edges toward the center a distance substantially the depth of the bellows tucks, the creases being formed in the opposite sides of the tubing and its tucks in a direction toward the inside of the tubing, cutting the tubing through all of its plies leaving a narrow uncut connection in

one side of the tubing, spreading the end of the tubing into the diamond form, defining the line 12, 12, when the diamond is being spread, flattening the diamond and applying paste, severing the narrow uncut 15 connection 10, and forming the final folds 14 and 15.

In testimony whereof I have signed my name to this specification in the presence of two subscribing witnesses.

ASA L. PARRISH.
